UNITED STATES PATENT OFFICE.

ANDREW P. WATT, OF BALTIMORE, MARYLAND.

DESIGN FOR A CASING FOR VENDING-MACHINES.

No. 40,043.

Specification for Design.

Patented June 8, 1909.

Application filed February 2, 1909. Serial No. 475,716. Term of patent 7 years.

To all whom it may concern:

Be it known that I, ANDREW P. WATT, a citizen of the United States, residing at the city of Baltimore, in the State of Maryland, have invented a new, original, and ornamental Design for a Casing for a Vending-Machine, of which the following is a specification, reference being had to the accompanying drawings, forming a part thereof.

The figure is a front elevation of a casing

for a vending machine, showing my new design.

I claim—

The ornamental design for a casing for a vending machine, as shown.

ANDREW P. WATT.
